Patented Oct. 14, 1919.

5 SHEETS—SHEET 5.

UNITED STATES PATENT OFFICE.

JOSEPH E. HOLBEIN, OF FOMBELL, PENNSYLVANIA.

MACHINE FOR PRESENTING TUBES TO GRINDERS.

1,319,000.

Specification of Letters Patent.

Patented Oct. 14, 1919.

Application filed March 5, 1919. Serial No. 280,687.

To all whom it may concern:

Be it known that I, JOSEPH E. HOLBEIN, a citizen of the United States, residing at Fombell, in the county of Beaver and State 5 of Pennsylvania, have invented certain new and useful Improvements in Machines for Presenting Tubes to Grinders; and I hereby declare that the following is a full, clear, and exact description thereof, reference being had to the accompanying drawings, which form part of this specification.

This invention is a novel machine especially designed for presenting seamless steel tubing to a grinder so that it may be 15 ground by such grinder to eliminate incipient seams or defects in the tubing preparatory to further reduction in diameter of the tube.

The invention includes novel means for 20 longitudinally feeding a tube past a relatively stationary grinder operating thereon, and for simultaneously rotating the tube on its axis as it is fed longitudinally forward; also novel means whereby the speed 25 of rotation of the tube relative to its longitudinal travel can be manually controlled and varied as desired; also novel means whereby the machine is adapted to handle tubes of varying diameter; also novel means 30 for imparting power continuously to the feeding units in whatever position they may be adjusted. The invention also includes various novel features of construction and novel combinations of parts as 35 hereinafter explained.

In the manufacture of seamless steel tubing the defects found in the tube blank after 40 passing through the hot mill must be ground out before the tube is cold drawn on the benches. These defects are fine seams in 45 the blooms and billets, which when the billets are pierced, develop into longitudinal circular or spiral seams of varying pitch and irregularity.

My novel machine is adapted, by reason 50 of the flexibility of the feeding units—which are always under the control of the operator—to enable the operator to bring the defects in the tube up to the stationary 55 grinder to be removed thereby in a facile and easy manner, and to lessen the manual labor required in grinding tubes, and enhance the speed and thoroughness of the grinding operations.

While the invention is particularly designed for use in grinding tubes as stated

it could also be adapted for rotating rods, or bars, etc., while the same are being fed longitudinally forward; and while I shall hereinafter refer to the object being treated 60 as a "tube" I use such word as a generic term to include tubes, rods, bars, and other objects which might be fed by such machine to a grinder or other means or mechanism operating thereon. I also use the word 65 "grinder" as a generic term to include any means or tool operating upon such "tube" while the latter is being manipulated by the machine.

To facilitate a comprehension of the invention I will explain in detail one practical embodiment thereof as illustrated in the accompanying drawings, but I refer to the claims for summaries of the essentials of 70 the invention, the various novel features of 75 construction, and various novel combinations of parts for all of which I desire protection. It should be understood, however, that the invention is not restricted to the particular mechanism shown in the drawings as when understood it may be embodied 80 in various designs and forms of machines which could differ in appearance and specific elements from that illustrated in the drawings while embodying the essentials of 85 the invention.

In said drawings:

Figure 1 is a top plan view of a complete machine for rolling or turning steel tubing and the like while the same is being operated upon by a relatively stationary 90 grinder.

Fig. 2 is a side view of Fig. 1 with the pipe removed.

Fig. 3 is an enlarged transverse sectional 95 view on the line 3—3, Fig. 2.

Fig. 4 is an enlarged partial side elevation showing the feeding units adjusted to a different position from that shown in Fig. 1.

Fig. 5 is an enlarged detail sectional view 100 of one of the sets of feeding units.

Fig. 6 is an enlarged sectional view of the head of one of the pipe retaining levers.

Fig. 7 is an enlarged sectional view of one 105 of the heads on line 7—7, Fig. 5.

Fig. 8 is a detail sectional view on line 8—8, Fig. 7.

Figs. 9, 10, 11, 12 and 13 are diagrammatic views illustrating various positions of the feeding heads and various movements 110 imparted thereby to the pipes.

The operative parts of the machine may

be mounted in a frame of any suitable make and form. As shown the frame may be mounted upon grooved wheels 1^b by which it can be adjustably supported and guided 5 on tracks 1^c, so that the machine may be readily moved to the desired working position, or to and from the grinder, or moved out of the way when not in use. Suitably journaled in this frame is a main shaft 2, 10 which extends longitudinally thereof, and may be driven at the desired speed from any suitable prime mover. In the machine shown the shaft 2 carries friction disks 2^a on one end, which disks engage a friction 15 roller 3^a slidably mounted on a vertical shaft 3, which is journaled in suitable bearings on the main frame at one end thereof.

In the machine shown the shaft 3 is geared to an electric motor indicated at M and 20 driven thereby, but instead of being geared to a motor the shaft may be driven either directly or indirectly from any other suitable prime mover. The roller 3^a may be adjusted radially of the disks 2^a by a link 25 3^b connected to a hand lever 3^c, which is provided with a latch and segment of the usual kind to hold it in any desired adjusted position. Such kinds of friction drives are old, and form no feature of the present invention; and any other suitable variable 30 speed drive may be used.

On shaft 2 is a series of spaced bevel gears 2^b that respectively mesh with bevel gears 4^b on the lower ends of vertically disposed 35 shafts 4, which are journaled in suitable bearings at the rear of the frame. As shown there are four such shafts 4, and each shaft 4 is geared to operate one pipe feeding and turning unit, or set of feeding heads. As 40 these units, in the construction shown, are duplicates, an explanation of one unit or set will explain all; similar letters being applied to similar parts in the several units or sets.

45 Referring particularly to Fig. 3, each shaft 4 has on its upper end a bevel gear 4^a which meshes with a bevel gear 5^a on a short shaft 5, that is disposed horizontally or transversely of the frame and journaled in 50 suitable bearings on the frame as shown. The inner end of shaft 5 is pivotally jointed to one end of a flexible or telescopic shaft member 5^b, the other end of which is pivotally jointed to the inner end of a stub shaft 55 6 journaled in a bearing 7^a on the upper end of a casting 7, which is pivotally mounted upon the frame at the front side thereof.

The member 5^b may be a telescopic shaft connection as indicated in the drawings, 60 such connection being well known needs no specific description herein; and various other flexible shaft connections well known in the art could be used to transmit rotary motion to the shaft 6 from the shaft 5 and 65 permit lateral displacement of the shaft 6

relatively to the shaft 5. The shafts 5 and 6 lie practically transversely of the frame and in axial alinement, but by reason of the flexible telescopic connection 5^b between the shafts 5 and 6, the shaft 6 is capable of being moved laterally relatively to shaft 5 while the rotative driving connection between the shafts 5 and 6 is maintained by the member 5^a.

70 As shown the casting 7 is rigidly connected to a shaft 7^b that is journaled in a suitable bearing 1^c on the front member of the frame; and said shaft may extend inward from the front bearing and have its rear end journaled in a bearing 1^d in the frame; so as to firmly support the casting 7 while permitting it to be swung laterally, and turn on or with shaft 7^b as its pivot.

75 On the front end of shaft 6 is a bevel gear 6^a which meshes with a similar bevel gear 6^b on the upper end of a stub shaft 6^c, which is journaled in a forwardly projecting arm 7^c of the casting 7 and disposed at right angles to the shaft 6. On the other end of shaft 6^c is mounted a feed head 6^e which 80 may be retained on the shaft by any suitable means; being shown as retained thereon by means of a screw 6^f tapped into the end of the shaft 6^c and concealed in a hole in the center of the head 6^e.

85 It is desirable to have the head 6^e connected to rotate with the shaft 6^c but capable of a partial independent rotary motion thereon, for a purpose hereinafter explained. As shown the head 6^e has an arc shaped slot 6^g in its base opposite an annular flange 6^h on the shaft 6^c, and a ball 6ⁱ is seated in a recess in the flange 6^h and projects into the slot 6^g and will permit a slight rotary motion of the shaft 6^c relative to head 6^e equal 90 to the length of the slot 6^g (see Figs. 7 and 8). However the shaft and head may be connected to have a limited amount of relative rotary motion in any other suitable and preferred manner.

95 110 Each shaft 4 also carries a bevel gear 14^a meshing with a gear 15^a on a stud shaft 15 suitably journaled in the frame parallel with and below the shaft 5, and connected by an extensible or flexible 115 shaft 15^b to a stub shaft 16 journaled in the lower end 17^a of a casting or bracket 17, which is mounted upon the frame below and opposite the casting 7, preferably by means of a shaft 17^b journaled in a bearing 1^{ex} on the frame opposite and below the bearing 1^c, and the inner end of the shaft 17^b may 120 be journaled in a bearing 1^{fx} below and parallel with the bearing 1^d, and suitably secured in the frame so as to support the casting 17 firmly on the frame while permitting it to be swung laterally on or with shaft 17^b as a pivot.

125 On the front end of shaft 16 is a bevel gear 16^a meshing with a bevel gear 16^b on 130

the lower end of a stub shaft 16^e journaled in the arm 17^e projecting forwardly from the bracket 7; and on the upper end of the shaft 16^e is mounted a feed-head 16^e similar, but reverse, to the head 6^e. The opposed heads 6^e, 16^e are adapted to coöperate in forwarding and turning a tube, and with their operating devices form a feed unit or set.

- 10 In the machine shown there are four units or sets of such coöperating and forwarding devices; each set being constructed alike and each being operated alike and simultaneously from the shaft 2.

15 The parts numbered 14, 14^a, 15, 15^a, 15^b, 16, 16^a, 16^b, 16^c, 17, 17^a, 17^b, 17^c, etc., are practically identical in construction to the parts 4, 4^a, 5, 5^a, 5^b, 6, 6^a, 6^b, 6^c, 7, 7^a, 7^b, 7^c, etc., and therefore do not need a more detailed explanation.

The heads 6^e, 16^e may be semi-spherical, conical, or tapered, but I prefer to make them semi-spherical as shown; and these heads may be of cast steel, or any other suitable metal or material that will be found best adapted to enable them to properly engage and operate upon the tube as herein-after explained.

The tube to be treated is adapted to be held in frictional contact with the faces of each pair of opposed heads 6° , 16° , by any suitable means, as indicated at T Figs. 3, 4, and 9 to 13.

35 A pressing or retaining member is provided adjacent each pair of feed heads 6° , 16° , to hold the tube in frictional contact with such feed heads. The form and arrangement of this pressing member may be varied and any desirable or suitable means 40 may be employed for holding the tube in frictional contact with the feed heads.

In the machine shown each pressing or retaining member comprises a lever 8 slidably supported at its lower end on a bracket 45 attached to the front of the frame below the shaft 16, and shown as connected therewith by a pin and slot connection 8^a, (see Fig. 3). This retaining lever extends upwardly from its support toward the shaft 50 16, and is then curved outwardly and upwardly and extends to a point slightly above the lower head 16^c. Below the shaft 16 the lever 8 passes through a slotted guide 55 9 attached to the front of the frame; which guide prevents lateral movement of the lever but permits it to have a swinging or oscillating movement toward or from the frame. An adjusting screw 9^a tapped through the outer end of the guide 9 engages the outer edge of the lever 8 and forms 60 a fulcrum on which said lever may oscillate. The fulcrum bolt 9^a may be locked in adjusted position by a jam nut 9^b.

The upper end of the retaining lever 8
65 is adapted to engage the side of the tube as

shown in Fig. 5, and hold the same against the adjacent feed heads 6^a, 16^e; and may be caused to engage and hold the tube against the heads by any suitable means. As shown a toggle 18 has one member pivotally connected to the lever 8 adjacent its lower end and its other member is pivoted to the frame as shown. The knuckle of the toggle is pivotally connected to the lower end of a link 18^b, the upper end of which is connected to a crank arm 18^c on a rock shaft 18^d, suitably supported on the main frame, and extending preferably to a point adjacent the drive end of the machine. Shaft 18^d can be provided with a crank handle 18^e by which it can be rocked.

When the crank 18^e is thrown to uppermost position the toggle 18 will be broken and the lower end of lever 8 moved toward the frame, causing the lever 8 to rock on the fulcrum bolt 9^a and its upper end to move away from the tube T and thus release the latter. When the crank 18^e is thrown in position to extend the toggle, as shown in Fig. 3, the lower end of lever 8 is pushed outwardly and the lever fulcrums on the bolt 9^a and its upper end contacts with the tube and holds the latter against the feed heads. The amount of pressure exerted by the lever 8 on the tube, and resultant pressure of the tube against the feed heads is regulated by adjusting the bolt 9^a. 85 90 95

To reduce or lessen friction between the pressing lever 8 and the tube T the upper end of the lever is preferably provided with 100 an antifriction contact device of any suitable construction. As shown in Figs. 3 and 6 this anti-friction device comprises a roller 8^e journaled in a slot in a casting 8^f that is pivotally connected to the upper end of lever 8 by a bolt 8^g so that the casting 8^f can turn on the lever, but said casting is preferably so formed or so weighted that it will normally 105 keep the roller 8^e on a vertical axis, or at right angles to the tube T. Preferably anti-friction means, such as balls 8ⁱ, is interposed between the base of the casting 8^f and the head of lever 8 so that the casting 8^f may 110 readily oscillate on the bolt 8^g and permit the roller 8^e to tilt slightly from a vertical 115 position as may be required when the tube T in addition to its longitudinal movement past the lever 8 is also being rotated on its own axis. Thus the roller 8^e can automatically 120 adjust itself to suit the movements of the tube and hold the latter against the feed heads with the least possible amount of retarding friction.

As shown each unit or set of feed heads is provided with a similar retaining device; and as each set of feed devices is constructed alike, similar parts being indicated by similar reference numerals, further illustration and explanation thereof is unnecessary. 125

As above stated, seams or incipient flaws 130

in the tubes are developed in the initial drawing process, and must be ground out before redrawing the tubes. These seams or flaws vary in direction and form. Most frequently these flaws are in spiral formation, and such spiral flaws may be substantially regular for any one piece of tubing; but the pitch of the spiral flaws in different tubes usually differ. It is therefore necessary, to enable the machine to act efficiently on all kinds of tubes, that the feed heads be adjustable and capable of not only forwarding the tubes longitudinally past the grinder, but also rotating the tubes in accordance with the pitch of the spiral flaws therein so that as the tube is fed past the grinder it will be rotated more or less rapidly according to the spiral pitch of the flaws and be fed past the grinder at such speed of longitudinal movement and rotary movement as will practically cause the spiral flaws, of whatever pitch, to be presented continuously to the grinder as the tube moves therewith.

The grinder, indicated at G, Fig. 1, may be a disk grinder of the usual type, and is preferably arranged at the side of the machine intermediate the two innermost sets of feed heads; the tube handling machine being movable bodily to or from the grinder, or vice versa, so that when a tube is entered in the machine it may be brought into contact with the grinder and held in contact therewith while the tube is fed longitudinally past the grinder. The grinder should be rotated at high speed while the tube is being fed therewith, and is in contact therewith, so that it will grind away the incipient seams or flaws in the surface of the tube. As these flaws are very shallow it does not require much grinding to obliterate them, but if they were not obliterated, in the subsequent redrawings of the tube the flaws would tend to deepen and render the tube worthless when reduced to the desired size.

The feed heads, 6^e, 16^e, in each set are relatively adjustable so that they can both feed a tube longitudinally and simultaneously impart a rotary motion thereto, and they may be adjusted even while in contact with a tube; and for this purpose the feed heads are preferably made semi-spherical, or so relatively shaped, that their axes may be adjusted to different relative angles while the heads still maintain effective contact with the tube.

As shown in Figs. 9 to 13 the heads may be shifted from a position in which their axes are in alignment end to end in the same plane; to a position in which their axes are parallel in different planes. Of course they may be adjusted to any intermediate position. When adjusted to the positions shown in Fig. 9 the tube would be fed straight through without any rotation. In the posi-

tion indicated in Fig. 10 the tube would be fed and rotated on its axis at about a 30° spiral. In Fig. 11 the tube would be fed and rotated at about a 45° spiral. In Fig. 12 the tube would be fed and rotated at about a 60° spiral; and in Fig. 13 the tube would be fed and rotated at about a 90° spiral. Thus by adjusting the relative pitch of the heads the operator can feed the tube and turn the same so that straight or spiral seams of any pitch or contour can be properly presented to the grinder as the tube is fed therewith. Any suitable means may be provided for adjusting these feed heads for the purpose specified.

In the machine shown each shaft 7^b has a crank arm 7^f that is pivotally connected to a link bar 7^s; which in turn is pivotally connected by a link 7^h to one arm of a lever 10, that is pivoted at 10^a on any suitable support on the frame. Each shaft 17^b has a crank arm 17^f pivotally connected to a link 17^s that is connected by a link 17^h to the lever 10 at the opposite side of the pivot 10^a of said lever. The pivotal connections of links 7^h and 17^h to the lever 10 are shown as equi-distant from the pivot 10^a of lever 10. The lever 10 is operatively connected by a link 10^b to a longitudinally movable slide bar 10^c mounted in a suitable guide 10ⁿ in the frame. Bar 10^c has a rack 10^d which meshes with a pinion 11^e on a shaft 11 suitably mounted in the frame and operable by a hand wheel 11^a. This hand wheel is preferably arranged adjacent the drive so that the operator can easily control the speed of the drive shaft 2 by manipulating the lever 3^c, and also by turning the hand wheel 11^a.

Operation.

When it is desired to grind a tube the machine and grinder are properly juxtaposed so that the grinder will be in position to operate upon the tube as it is fed therewith by the machine. The pressing levers 8 are properly adjusted relative to the feed heads 6^e, 16^e to suit the size of tube to be operated upon. The operator then sets off the pressing levers 8 from the two sets of heads 6^e, 16^e at the incoming end of the machine and enters the end of a tube T between such heads and the pressing levers, and then sets up the pressing levers so as to hold the tube in contact with the heads, as indicated in Fig. 3. Then he starts the machine in operation and the heads engaging the tube feed it to and past the grinder. The operator stands in a position where he can observe the twist of the spiral flaws in the tube and adjusts the inclination of the feed heads by manipulating wheel 11^a so as to cause the tube to be fed past the grinder at the desired rate of speed and with such a twisting or rotating movement as will cause the tube to present the spiral flaws therein

to the grinder. The operator can vary the speed of the feed and rotation of the tube according to the pitch of the spiral flaws in the tube, by adjusting the relative inclination of the opposed feed heads in each pair or unit, as above explained.

To facilitate the adjustment of the heads while in engagement with the pipe, each head is preferably so connected with its shaft as to permit a partial relative rotation between the head and its shaft, as indicated in Figs. 7 and 8; for the reason that to adjust the heads in one direction they must be shifted in the direction in which they are rotating; and to adjust them in the other direction they must be shifted contrary to the direction in which they are rotating. By mounting the heads on their shafts so as to permit partial relative rotation the latter adjustment is facilitated.

As the tubes are usually long and preferably straight I prefer to have the tube operatively held by only two sets of the feed heads at a time; thus, if the tube is entered 25 between the first two sets, at the right in Fig. 1, then after its end has engaged the third set of feed heads the pressing lever of the first set of feed heads can be released by shifting its controlling lever 18° 30 and leaving the tube under control of the two intermediate sets of feed heads; and then when the tube end enters the fourth set of feed heads the pressing lever of the second set of feed heads may be released. This 35 will lessen strain on the machine and facilitate the treatment of slightly bent tubes. The machine can be operated rapidly and efficiently, and will greatly facilitate the operation of grinding the tube; save time 40 and labor in such operation, and produce better results.

It will be seen that the operator has the work always under his direct control; and that the tube is positively held and fed to 45 the grinder by mechanism always under the control of the operator, and the labor involved in manually holding the tube against the grinder, as is now the practice, is done away with; and better and more accurate 50 grinding obtained; and the tubes can be readily and quickly ground, as desired.

What I claim is:

1. In a machine for presenting tubes to a grinder, means for feeding a tube longitudinally past the grinder and rotating it on its axis to present spiral flaws in the tube to the grinder; with means for varying the speed of travel and rotation of the tube past the grinder during the grinding operation.

2. In combination with a grinder, means for feeding a tube longitudinally past the grinder and means for simultaneously rotating the tube on its axis so that the grinder 65 can follow spiral flaws in the tube; with

manually controlled means for varying the speed of travel and rotation of the tube past the grinder during the grinding operation.

3. In a machine for presenting tubes to a grinding mechanism, etc., means for feeding a tube longitudinally past the grinder, and means for simultaneously rotating it on its axis to present spiral flaws in the tube to the grinder; with manually controlled means for varying the travel and rotation of the tube past the grinder.

4. In a machine for presenting tubes to a grinder, semi-spherical feed heads adapted to both feed a tube longitudinally and simultaneously rotate the tube.

5. In combination, a grinder, and adjustable feed heads adapted to both a tube longitudinally past the grinder and simultaneously rotate the tube and means for adjusting the heads during a grinding operation to vary the feed.

6. In combination, feed heads adapted to both feed a tube longitudinally and simultaneously rotate the tube; with means for adjusting the heads at varying angles to the tube during a grinding operation to vary the speed of feed and rotation of the tube.

7. In combination, a grinder; feed heads adapted to both feed a tube longitudinally past the grinder and simultaneously rotate the tube; and manually operable means for adjusting the heads to vary the speed of feed and rotation of the tube.

8. In a machine for presenting tubes to a grinding mechanism, the combination of sets of related rotatable feed heads adapted to both feed a tube longitudinally past the grinder and simultaneously rotate the tube; with manually operable means for adjusting the heads at varying angles to the tube.

9. In combination, a grinder; feed heads adapted to both feed a tube longitudinally past the grinder and simultaneously rotate the tube; and means for adjusting the heads while in contact with the tube, to vary the speed of feed and rotation of the tube, at varying angles to the tube.

10. In a machine for presenting tubes to a grinding mechanism; the combination of a plurality of sets of coacting feed heads, means for adjusting the heads to vary the feed of the tube during a grinding operation, means for rotating the heads, and means for holding a tube in frictional contact with said heads.

11. In combination, opposed coacting feed heads, means for holding a tube in frictional contact with said heads; means for rotating the heads on their axes; and means for adjusting the heads at varying angles to the tube.

12. In combination, a grinder; opposed coacting feed heads, means for holding a tube in frictional contact with said heads; means for rotating the heads on their axes; and

operable means for manually adjusting the heads at varying angles to the tube to vary the speed of and rotation of the tube.

13. In a machine for the purpose specified, the combination of a grinder; a plurality of sets of opposed coacting feed heads adapted to frictionally engage a tube; means for rotating the heads on their axes; means for holding a tube in frictional contact with said heads; and manually operable means for adjusting the heads at varying angles to the tube.

14. In a machine for the purpose specified, feed heads adapted to engage a tube, means for rotating the heads, a lever for holding a tube in frictional contact with said heads; and means for adjusting said lever.

15. In combination, opposed coacting feed heads adapted to frictionally engage a tube, means for rotating the heads, a lever for holding a tube in frictional contact with said heads; manually controlled means for adjusting said lever, and manually operable means for adjusting the heads at varying angles to the tube to vary the speed of feed and rotation of the tube.

16. In combination, a plurality of sets of coacting feed heads adapted to frictionally engage a pipe or rod; means for rotating the heads on their axes; a lever adjacent each pair of heads for holding a tube in frictional contact therewith; means for adjusting said levers, and means for adjusting the heads at varying angles to the tubes, substantially as described.

17. In a machine for the purpose specified, the combination of a plurality of sets of opposed coacting feed heads adapted to frictionally engage a pipe or rod; means for rotating the heads on their axes; a lever adjacent each pair of heads for yieldingly holding a tube in frictional contact therewith; manually controlled means for adjusting said levers; and manually controlled means for adjusting the heads at varying angles to the tube to vary the speed of feed and rotation of the tube, substantially as described.

18. In combination, a pair of similar but opposite feed heads, a rotatable shaft carrying each head, a gear on each shaft, adjustable brackets supporting said shafts, relatively stationarily mounted driving gears and flexible driving connections between the said driving gears and the gears on the shafts.

19. In combination, a pair of similar but opposite feed heads, a rotatable shaft carrying each head, a gear on each shaft, adjustable brackets supporting said shaft, arms connected with said brackets, slidable bars connected with said arms, and means for simultaneously operating said bars so as to adjust the heads to different angles.

20. In combination, a pair of similar but opposite feed heads, a rotatable shaft carrying each head, a gear on each shaft, adjustable brackets supporting said shaft, arms connected with said brackets, slidable bars connected with said arms, and means for simultaneously operating said bars so as to adjust the heads to different angles; with driving gears and flexible driving connections between the said driving gears and the gears on the shafts of the feed heads.

21. In a machine of the character described, a semi-spherical feed head, a shaft on which this head is mounted, and means for permitting partial relative rotation between the shaft and the head.

22. In a machine of the character described, a semi-spherical feed head, a shaft on which this head is mounted, and means for permitting partial relative rotation between the shaft and the head; with means for swingably supporting the shaft; and means for imparting rotary motion to said shaft in all positions of the head.

23. In a machine of the character described, feed heads, a pressing lever, a toggle connected with the lower end of the lever, an adjustable fulcrum for the lever between the toggle and the heads, and means for adjusting the toggle to oscillate the lever on its fulcrum.

24. In a machine of the character specified, a pressing head, an anti-friction self-adjusting device pivotally connected with the head and adapted to engage the work, and means for adjusting the head to press the device against the object being operated upon.

25. In a machine of the character specified, tube feeding means, a presser, an anti-friction self-adjusting device connected with the presser adapted to engage the work, and means for adjusting the presser so as to hold the device in contact with the tube.

26. In a machine of the character specified, a pair of feed heads, a presser lever, an anti-friction roller, a support for said roller pivotally connected with the lever; and means for adjusting the lever to cause the anti-friction roller to hold a tube in contact with the head.

27. In a machine of the character specified, the combination of a driven shaft, upper and lower gears on said shaft, upper and lower feed heads, shafts respectively carrying said feed heads, and gearing between the upper and lower feed heads and upper and lower gears on the driven shaft.

28. In a machine of the character specified, the combination of a driven shaft, upper and lower gears on said shaft, upper and lower feed heads, shafts respectively carrying said feed heads, and gearing between the upper and lower feed heads and upper and lower gears on the driven shaft; with means

whereby the said heads may be adjusted to various relative positions while maintaining their geared connection.

29. In a machine of the character specified, the combination of a driven shaft, upper and lower gears on said driven shaft, upper and lower feed heads, shafts respectively carrying said heads, and connections between the gears on the said head shafts 10 and the gears on the driven shaft, said connections permitting swinging movements of the heads relatively to the driven shaft.

30. In a machine of the character specified, the combination of a driven shaft, upper and lower gears on said shaft, upper and lower feed heads, shafts respectively carrying said heads; swingable supports in which said head shafts are journaled; connections between the gears on the said head shafts 20 and the gears on the driven shafts, said connections permitting rocking movement of the heads, and means for adjusting said swingable supports to vary the positions of said heads.

31. In a machine of the character specified, the combination of a driven shaft, upper and lower gears on said shaft, upper and lower feed heads, shafts respectively carrying said feed heads, and gearing between the upper and lower feed heads and upper and lower gears on the driven shaft; with an adjustable presser lever adjacent the heads, a toggle for throwing the lever into or out of operative position; manually controlled devices for operating said toggle, and manually controlled devices for adjusting the relative position of the heads.

32. In a machine of the character specified, the combination of a driving shaft, a series of gears thereon, a series of counter shafts respectively geared to the gears on the driving shaft, upper and lower gears on said counter shafts, pairs of upper and lower feed heads, shafts respectively carrying said heads, and gearing between each pair of upper and lower feed heads and upper and lower gears on the related counter shaft.

33. In a machine of the character specified, the combination of a driving shaft, a series of gears thereon, a series of counter shafts respectively geared to the gears on the driving shaft, upper and lower gears on said counter shafts, pairs of upper and

lower feed heads, shafts respectively carrying said heads, and gearing between each pair of upper and lower feed heads and upper and lower gears on the related counter shafts; with means whereby the said heads may be adjusted to various relative positions 60 while maintaining their geared connection.

34. In a machine of the character specified, the combination of a driving shaft, a series of gears thereon, a series of counter shafts respectively geared to the gears on the driving shaft, upper and lower gears on said counter shafts, pairs of upper and lower feed heads; shafts respectively carrying said heads; and connections between the gears on the said head shafts and the gears 70 on the related counter shafts, said connections permitting rocking movements of the heads.

35. In a machine of the character specified, the combination of a driving shaft, a series of gears thereon, a series of counter shafts respectively geared to the gears on the driving shaft, upper and lower gears on said counter shafts, pairs of upper and lower feed heads; shafts respectively carrying 80 said heads; swingable supports in which said head shafts are journaled, means for adjusting said swingable supports to vary the relative positions of said heads; and connections between the gears on the said 85 head shafts and the gears on the related counter shafts, said connections permitting rocking movements of the heads.

36. In a machine of the character specified, the combination of a driving shaft, a series of gears thereon, a series of counter shafts respectively geared to the gears on the driving shaft, upper and lower gears on said counter shafts, pairs of upper and lower feed heads, shafts respectively carrying 95 said heads, and gearing between each pair of upper and lower feed heads and upper and lower gears on the related counter shaft; with an adjustable presser lever adjacent each pair of heads, a toggle for throwing each lever into or out of operating position; manually controlled devices for operating each toggle; and manually controlled devices for adjusting the relative position of the feed heads.

In testimony that I claim the foregoing as my own, I affix my signature.

JOSEPH E. HOLBEIN.
